UNITED STATES PATENT OFFICE.

DAVID GROTTA, OF NEWARK, NEW JERSEY, ASSIGNOR TO WEINGARTEN BROS., INC.,
OF NEW YORK, N. Y., A CORPORATION OF NEW JERSEY.

DESIGN FOR A CORSET.

43,531.

Specification for Design.

Patented Feb. 11, 1913.

Application filed September 17, 1912. Serial No. 720,905. Term of patent 7 years.

To all whom it may concern:

Be it known that I, DAVID GROTTA, a citizen of the United States, residing at Newark, in the county of Essex and State of New Jersey, have invented a new, original, and ornamental Design for Corsets, of which the following is a specification, reference being had to the accompanying drawing, forming part thereof.

The figure is a perspective view of a corset showing my new design.

I claim:

The ornamental design for a corset, as shown.

DAVID GROTTA.

Witnesses:

OTTO MUNK,
CLARISSA FRANCK.
